UNITED STATES PATENT OFFICE.

JOHN SMITH, OF BIRMINGHAM, ENGLAND.

DESIGN FOR A CHAIN-LINK.

SPECIFICATION forming part of Design No. 30,242, dated February 21, 1899.

Application filed May 10, 1898. Serial No. 680,323. Term of patent 14 years.

To all whom it may concern:

Be it known that I, JOHN SMITH, a subject of the Queen of Great Britain, and a resident of Birmingham, England, have invented and

5 produced a new and useful Design for a Chain-Link, of which the following is a specification.

My design is illustrated in the accompanying drawings, in which—

Figure 1 is a side elevation, and Fig. 2 an 10 end view.

The leading feature of my design consists of a solid block-link having a flat upper face B' and a double-curved lower face B, merging at each end into the reverse curve B³, which 15 forms an acute angle with the flat upper face.

Cylindrical openings B² appear, extending through from side to side, and centrally of these and slightly above the same is a smaller opening b.

Having thus described my invention, what 20 I claim is—

The design for a chain-link substantially as shown and described.

In witness whereof I have hereunto set my hand in presence of two witnesses.

JOHN SMITH.

Witnesses:

EDWARD MARKS,
HERBERT BAWKETT.
